UNITED STATES PATENT OFFICE

133,634

DESIGN FOR AN AIRPLANE

Robert W. Huzzard, York, Pa., assignor of two-thirds to George H. Whiteley, III, York, Pa.

Application May 22, 1941, Serial No. 101,084

Term of patent 14 years

To all whom it may concern:

Be it known that I, Robert W. Huzzard, a citizen of the United States and a resident of York, in the county of York and Commonwealth of Pennsylvania, have invented a new, original, and ornamental Design for an Airplane, of which the following is a specification, reference being had to the accompanying drawings, forming a part thereof.

Figure 1 is a top perspective view of an airplane embodying my new design with the parts thereof shown in flight position,

Figure 2 is a bottom perspective view of the

airplane illustrated in Figure 1 with the parts thereof arranged in flight position,

Figure 3 is a view similar to Figure 2, but wherein the parts are arranged in landing position,

Figure 4 is a side elevational view with the parts arranged in landing position, and

Figure 5 is a front elevational view of the parts arranged in flight position.

I claim:

The ornamental design for an airplane, as shown.

ROBERT W. HUZZARD.
